INVENTOR:

Franklin R. White,
Parker Cook

ATTORNEY

UNITED STATES PATENT OFFICE

FRANKLIN R. WHITE, OF WATERBURY, CONNECTICUT, ASSIGNOR TO THE PATENT BUTTON COMPANY, OF WATERBURY, CONNECTICUT, A CORPORATION OF CONNECTICUT

BUTTON

Application filed October 2, 1929. Serial No. 396,863.

My invention relates to new and useful improvements in buttons, and more particularly to a button of the type or class shown in a previous patent granted to me, No. 5 1,538,015, on May 19, 1925.

In that patent, the body of the button was described as made from a slug or blank of malleable metal, such as aluminum or zinc, this metal forming the body or rim on which 10 was placed a cap, and also forming the hub of the button into which the tack fastener was to be driven.

One of the objects of the present invention is to provide a similar type of button, 15 but instead of using a slug to form the body of the button, I use a small shell and a cover or cap, which contains a soft metal ring that is rigidly forced in the cap to form substantially a unitary structure.

Again, instead of using a ring, I may use 20 a relatively thin disk of aluminum which is to be united with the cap to give the cap the desired shape and strength and into which cap is then secured a small shell which forms 25 the body of the button.

Still another object of the invention is to provide a button wherein a brass or other 30 similarly formed metal cap has placed therein a small ring or disk of soft or malleable metal, the cap and ring or disk being then subjected 35 to suitable dies to thereby effect a rigid attachment between the cap and said disk or ring, after which the cap may be swedged or pressed about a metal shell to thereby complete the button head.

Still another object of the invention is to provide an ornamented cap in which there is 40 placed a small amount of soft metal, so that when the cap is subjected to pressure, the soft metal will force the cap to any shape desired and will form a rigid attachment therewith, after which a relatively cheap shell may be secured within the rim of the cap, which shell, 45 of course, will afterwards receive a tack or staple fastener.

Still another object of the invention is to provide what is known as a high grade button, wherein the cap preferably brass, may be forced to any desired shape and have any desired insignia thereon, and wherein a rela-

tively small amount of malleable or soft metal, preferably aluminum, is utilized to add strength and body to the cap, after which a relatively cheap shell may be forced within the cap and the cap rimmed to thus afford a 55 permanent attachment between the shell and cap and complete the button head.

With these and numerous other objects in view, the invention consists in certain new and novel arrangements and combination of 60 parts, that will be more fully described and pointed out in the claims.

Referring now to the drawings showing a preferred embodiment,

Fig. 1 is a plan and section of the cap 65 greatly exaggerated for sake of clearness;

Fig. 2 is a similar plan and section of a disk or soft metal blank;

Fig. 3 is a plan and section of a soft metal 70 ring, the dotted lines showing the cap;

Fig. 4 is a plan and section of the blank or disk fitting within the cap;

Fig. 5 is a plan and section of the cap and blank after the same have been subjected to 75 heading dies;

Fig. 6 is a sectional view of a die for joining the cap and disk, as shown in Fig. 5;

Fig. 7 is a reduced sectional view showing a complete assembly;

Fig. 7 shows a slightly modified form 80 where the ring of soft metal is used and an additional anvil, which may be in the form of a hard metal disk;

Fig. 8 is a view in elevation of a button, as 85 attached to the goods.

Referring now more particularly to the several views, and for the moment to Fig. 1, there is shown a metal cap 1, which may be formed of brass and may be ornamented with insignia, trade-marks, or other desired subject matter, as there is a certain large class in the trade (manufacturers of overalls) that requires buttons of this character. For the purpose of illustration, however, I have simply shown a plain cap free from ornamentation.

This cap 1 is provided with the upstanding peripheral flange 2, which is to be greater in height than the thickness of a small ring 3. This ring 3 is preferably made of aluminum 100

and is designed to just loosely fit within the rim 2 of the cap 1, as may be understood from Fig. 3.

Now in Figs. 2 and 4, I have shown a 5 filler of slightly different form, that is, instead of using a ring 3, I have shown a small metal disk 5, which is also to be formed of aluminum or other desired soft metal, and likewise this loosely fits within the cap before the cap and disk are subjected to the dies.

It will be understood that I may use either 10 the disk or the ring. However, if the ring 3 is utilized rather than the disk, I employ an additional hard metal disk 6, which may be placed within the cap, which disk is less in 15 diameter than the ring 3, and this hard metal disk will reinforce the button head, so that the button head will not become bent or disfigured 20 when the tack fastener is to be driven up within the hub. In other words, the disk 6 is an anvil to deform the tack fastener.

Referring now for the moment to Fig. 5, 25 there is shown the cap 1 in which there has been placed say the soft metal disk 5, this cap and disk having been subjected to a heading die 7.

This die is simply fragmentarily shown, 30 comprising a plunger 8 fitting within the blocks 9 while the space 10 is shown, into which the metal cap may be forced.

It might be here mentioned that when the 35 brass cap with a soft metal ring or disk is subjected to great pressure in a die of this kind, the soft metal will force the brass shell to the desired shape, that is, to the shape of the dies.

In Fig. 5, it will be seen that this cap 1 rather than being a plain circle is now provided 40 with the scallops 11, the soft metal, due to pressure of the plunger, forcing the cap and part of the soft metal to the shape of the die.

It will also be understood that the die can 45 be of any desired form, both as to the rim and face, and that the soft metal disk or ring can be such as to meet the requirements. For instance, the outline of the button might be hexagonal or octagonal or, in fact, any outline, rather than provided with the scallops, as shown.

When the cap and soft metal insert are subjected to the dies, as shown in Fig. 6, an enormous pressure is used, so that metals are, in a 55 sense, amalgamated and jointed together, so as to practically form a rigid unit.

After these caps are so formed, a previously formed body or shell 12 is fastened within the rim 2 of the cap and the rim 2 then swedged 60 or pressed over the peripheral rim 13 of the body of the shell.

Of course, this is also done by dies and although I have not shown a die for this purpose, it will be readily understood by those 65 skilled in the art.

It will be noticed that the rim 2 of the cap is of such height that there is material enough left to bend over the shell or body and thus tightly hold the cap and shell together to complete the button head.

In Fig. 7^a, I have shown the cap in which 70 there has been pressed the metal ring 3, or might even have had the disk 4 pressed therein, and there is also shown the additional hard metal plate or anvil 6.

In this Fig. 7^a, I have also shown an imperforate hub and an anchor or die 14, so that the tack 15 may be driven up into this hub and within the anchor or die, as is the common practice, but it will be understood that this anchor or die 14 might be dispensed with if the hard metal disk 6 is used. Any desired type of anvil might be employed to mutilate the prong of the tack 15 when it is driven into the hub of the button or, in other words, the gist of 80 the invention is the manner in which the cap, together with its filler, is made, together with the body shell, rather than the formation of the hub and the manner of receiving the tack fastener.

From the foregoing, it will be seen that I 85 have provided a button wherein the cap may be of brass and ornamented as desired to suit the trade.

It will also be seen that by using a small disk 90 or ring of soft malleable metal, I can strengthen the cap and, at the same time, force the brass cap, without fear of mutilation, into the shape and form desired.

Lastly, I can take the brass cap, and by placing but a small amount of aluminum therein 100 press the cap to the shape and configuration desired, and then take a relatively cheap body shell and rim the cap over the shell to thus complete an exceedingly strong and efficient, 105 as well as an ornamental, button head, and all at a reasonably low cost.

It will be understood that although I have 110 shown the body shell of certain formation, I might utilize other desired forms of body shells, for instance such as shown in the patent granted to me and Leonard R. Carley for flexible buttons, No. 1,718,843, dated June 25, 1929, which shows a flexible body shell. In other words, any desirable form of shell might 115 be used, as the shell per se does not form the gist of the present invention.

Having described my invention, what I 120 claim as new and desire to secure by Letters Patent is:

1. A button head comprising a body of shell formation, a cap having a soft metal insert pressed to distortion within the peripheral rim of the cap to form a substantially unitary cap and the rim of said cap being pressed over the body shell.

2. A button head composed of a shell body, 125 a cap mounted upon the shell, the said cap forming a non-separable unit with the shell, the periphery of the cap being irregular in 130

shape and said cap having a soft metal insert pressed to distortion within the irregular periphery of the cap.

3. A button formed of metal having a shell body and circular upper rim, a circular cap mounted on said rim and the cap having an irregularly shaped periphery, the said cap having a soft metal insert and pressed in the irregularities of the cap and the said cap having its rim pressed down upon the rim of said shell to form a nonseparable unit.

4. A button head comprising a body of shell formation, a circular cap having a metal insert fitting therein and pressed to distortion within the peripheral rim of the cap to form a rigid and substantially unitary cap and the rim of said cap being pressed over the body of the shell to form the complete button head.

5. A metal button comprising a shell body adapted to receive a tack fastener, said shell body having an upper rim, a metal cap having a peripheral flange, a disk of relatively soft metal fitted within said cap and compressed into the inner peripheral edge of the cap, the soft metal disk and the metal cap forming a unitary structure and the rim of the cap being swedged over the shell rim of the body.

6. A metal button comprising a body having a peripheral rim, said body adapted to receive a tack fastener, a metal cap having a filler of relatively soft metal and the soft metal and the cap being pressed to form an irregular periphery about the cap, the soft metal and the cap being substantially a unitary structure and the rim of the cap being clamped over the rim of the shell body.

7. A metal button comprising a cap, a disk of aluminum fitting therein, said cap and said disk being pressed to form an irregularly shaped outline cap and ornamentation in the cap the soft metal filling the irregularities in the periphery of the cap and forming a substantially integral structure with the cap, a body adapted to receive a tack fastener and the said cap tightly encircling said body to thereby complete the button head.

8. A button comprising a body adapted to receive a fastener, a cap having a soft metal insert, the soft metal insert pressed to distortion into the peripheral edge of the cap to form an irregularly shaped cap and to strengthen the cap, a shell body having an anvil therein, the body adapted to receive a tack fastener and the cap swedged about said shell body to complete the button head.

In testimony whereof I affix my signature.
FRANKLIN R. WHITE.
